H. A. Richards,
ATTORNEY.

UNITED STATES PATENT OFFICE.

CARL A. LIND, OF MALDEN, ILLINOIS.

RAIL ANCHOR.

1,117,203.

Specification of Letters Patent. Patented Nov. 17, 1914.

Application filed April 25, 1912. Serial No. 698,049.

To all whom it may concern:

Be it known that I, CARL A. LIND, a citizen of the United States, and a resident of Malden, in the county of Bureau and State of Illinois, have invented a new and useful Rail-Anchor, of which the following is a specification.

My invention relates to devices for preventing railroad rails from "creeping" with reference to the ties on and to which they are spiked.

The invention has for its main object to provide a simple, durable, strong and effective device of the nature recited, which may be readily applied and positioned and as readily removed.

More specifically stated, some of the objects are to provide an improved rail-anchor which will effectively grip the rail flanges when applied thereto and which will not loosen or relax its grip thereon when the pressure between the anchor and tie is released or relaxed; which has a minimum of friction between the interlocking parts of the anti-creeper or anchor and a maximum of friction between said parts and the rail base (or flanges) gripped thereby; which has a comparatively large angle of sliding engagement for the relatively movable parts of the anchor to provide for a "take-up," whereby the anchor may be applied to rails of various widths, and which anchor has parts that are positively locked against a movement that would tend to loosen their grip on the rail base but which may be disengaged when desired without mutilating or breaking the locking means.

To the end of carrying out these objects the invention consists in certain novel features of construction and certain novel combinations of parts, as will be hereinafter described and pointed out in the appended claims.

A preferred embodiment of my invention is illustrated in the accompanying drawings, in which the elements and the parts or portions comprising which are, wherever applied in the several views, each designated by a distinguishing reference character.

In said drawings: Figure 1 is a plan view, showing my improvements as applied to a railway tie and rail, both of which latter are partly broken away; Fig. 2, a transverse sectional view, taken in the line 2-2 and seen in the direction of the arrow in Fig. 1; Fig. 3, a perspective detail of the base-ele-

ment or rail-seat; Fig. 4, a like detail of the binding-block; and Fig. 5, an end elevation, seen from the binding-block side.

Considering the drawings, 2 designates a railway tie, and 3 an ordinary rail, the flanges 4 of which are secured thereon by spikes 5. These may be of any preferred construction.

6 designates a base-element or rail-seat which may be termed a clip and comprises a main or body portion 7 provided at its ends with overhanging lugs or jaws 8, 8' which afford ways 9, 9'. Its upper face is cut away to provide a recess 10, one shoulder, 70, 11, of which is preferably inclined or diagonal to a transverse central line, the other wall being provided by the lug 8'. Running transversely of the body 7 and bisecting that portion thereof which provides the recess 10 is a diagonally arranged key-way 13, at least one wall, 12, of which is undercut or wedge-shaped and the bottom of which lies in a plane lower than that of the recess 10. Projecting downwardly from the edge of the base is an abutment 14, which is reinforced by a transverse rib 15.

16, 16' are beads or ribs on the lugs 8, 8' respectively.

17 designates a binding-block or mate and comprises a plate-like base 18 provided on its lower surface with a transversely arranged projection or key 19 having an undercut or wedge-like wall 19' and on its upper surface with an overhanging lug or jaw 20 providing a way 21. The forward end of the outer portion 24 projects forwardly and is provided with a series of apertures 22 for the selective placements of a cotter 23.

25, 25 are reinforcing beads.

In operation: Assume the parts to be disassembled. To assemble them the seat 6 is placed beneath the rail, one flange of which rests snugly in the way 9. The face of the abutment 14 rests snugly against the side of a tie 2. Thereupon the binding-block is positioned from the rear edge of the base 6 and forcibly slidably engaged therewith, as by driving,--the plate 18 entering the recess 10, and the key 19 entering the inclined recess 13 and binding against the inclined wall 12 thereof to gradually force the key and thereby the block toward the rail and bind or lock the latter in an evident manner 110 between the lugs 8 and 20. The projection 24 fits and moves within the way 9', whereby

the outer end of the block is restrained by the lug 8' from rising, its inner portion being restrained by the key 19. It will be evident also that the diagonal—or simultaneous transverse and longitudinal—movement of the binding-block does not destroy the parallelism of the faces or walls providing the ways 9 and 21, and that whatever be the position of said block the rail flanges will be firmly engaged thereby. If by reason of wear it should ever become necessary to tighten the rail, by driving the block forwardly the wall 19' will by reason of its transverse inclination be further forced by the opposed wall 12 toward the rail to more tightly bind it against the lug 8. It will be evident that by bending the apertured end of the projection 24 downwardly no key or other extraneous means will be required to prevent the mate 17 from becoming loosened from the clip 6; and it will be further evident that should wear occur it may be again bent to again tighten said elements relatively to each other. When so used the holes 22 may be omitted. Being preferably constructed of malleable iron the projection will bend without breaking, and it may be bent back when desired, in order to remove the mate from the clip. Selective placements of a cotter or pin 23 may be made in the holes 22 therefor provided. It is to be noted that notwithstanding the mate 17 is substantially inclosed by the jaw 8', said jaw performs no direct function in maintaining the parts in wedging engagement, as said engagement takes place entirely beneath the rail base. As a result there is no friction between said mate and jaw aside from a possible friction between the projection 24 and said jaw, due usually to a warped casting or to one having an unnoticed enlargement. There is greater friction, of course, between the interlocking walls 12 and 19', but even this is relatively slight compared with the friction developed between the jaws 8 and 20 and the opposite sides of the rail base, as said jaws grip the rail base both above and below and there is greater pressure at these points than at the points of contact of or between the co-acting members of the anchor.

It has been thought neither necessary nor best to encumber this specification and the accompanying drawings with descriptions and illustrations of elements or of modifications which are neither material nor essential to, nor form any part of the invention claimed. In fact, it is apparent even in the absence of such that numerous changes may be made in the details of construction, and by modifications involving mechanical skill only, without departing from the general idea of the invention.

Therefore, without limiting myself to particularities or to the details of construction

shown, I claim as my invention the following, to-wit:

1. A device of the character described comprising a rail-seat having an overhanging lug at each of its ends and a transversely inclined undercut groove in its upper face, and a binding-block adapted for engagement with one of said lugs and with said inclined groove. 70

2. A base for rail-anchors, said base having in its face an undercut rail-seat, a binding-block seat therebelow, and a key-seat disposed beneath the last recited seat. 75

3. A rail-anchor base having at its ends overhanging lugs and its face provided with a rail-flange seat, a binding block seat therebelow, and an undercut key-seat disposed beneath the last recited seat. 80

4. A rail-anchor base having at its ends overhanging lugs and its face provided with a rail-seat, a binding-block seat therebelow, and an undercut key-seat in a plane lower than that of the binding-block seat. 85

5. A rail-anchor comprising in combination a base having in its face a rail-seat, and having a binding-block seat therebelow and an undercut key-seat below the last recited seat, and a binding block provided with a key, said block adapted for engagement with the last recited seats. 90

6. A device of the character described comprising a base-element having an overhanging lug at each of its ends whereby ways are provided, and having in its face an upper and a lower recess, the last recess diagonally arranged, a rail-binding block adapted to seat and slide in the first recited recess and one of its ends in one of said ways, said block having an overhanging lug providing a way confronting the other one of said ways in said seat, there being means adapted to engage said lower recess, and means for locking said elements together after operative placement. 100

7. A device of the character described comprising a rail-seat having an overhanging lug at each of its ends whereby ways are provided and having in its face an upper and a lower recess, the last recited recess being diagonally arranged, and a rail-binding block adapted to seat and slide in the first recited recess and one of its ends in one of said ways, said block having an overhanging lug providing a way confronting the other one of said ways in said seat, and provided also with a transversely arranged key adapted for sliding movement in said lower recess. 115

8. A rail-anchor comprising relatively movable members adapted to grip opposite sides of the rail base, one of said members having a tie-abutting flange and having also a jaw within which the other of said members fits loosely, said members having portions sliding one upon the other when the 120

parts are driven into firm wedging engagement, the area of said portions which are in frictional engagement being less than the area of frictional engagement of said other member with said rail-base.

9. A rail anchor comprising two members each having a jaw for gripping the rail base, one of said members fitting loosely within and being substantially inclosed by a portion of the other of said members, the friction between said interfitting portions being less than the friction between the first member and the rail base.

10. A rail-anchor comprising relatively movable members adapted to grip opposite sides of the rail-base, one of said members having a tie-abutting flange and having also a jaw within which the other of said members fits loosely, said members having portions sliding one upon the other when the parts are driven into firm wedging engagement, the area of said portions which are in frictional engagement being less than the area of frictional engagement of said other member with said rail-base, and means for locking said members from separation after they have been operatively positioned.

11. A rail-anchor comprising two members each having a jaw for gripping the rail base, one of said members fitting loosely within and being substantially inclosed by a portion of the other of said members, the friction between said interfitting portions being less than the friction between the first member and the rail base, and one of said elements having an apertured portion whereby they may be held from separation after being operatively engaged.

12. A rail-anchor comprising a base element having an overhanging lug at one of its ends whereby a way is provided, and a rail-binding block a portion of which is adapted to seat and slide in said way, said block provided with an apertured projection whereby it and said base element may be locked from separation after being operatively engaged.

In witness whereof I hereunto affix my signature this 21st day of February, 1912.

CARL A. LIND.
